(57) **CLAIM**

The ornamental design for a beverage bottle, as shown and described.

DESCRIPTION

FIG. 1 is a perspective view of the beverage bottle;

FIG. 2 is a front view of FIG. 1;

FIG. 3 is a rear view of FIG. 1;

FIG. 4 is a left-side view of FIG. 1;

FIG. 5 is a right-side view of FIG. 1;

FIG. 6 is a bottom view of FIG. 1; and,

FIG. 7 is a top view of FIG. 1.

The broken lines depicting the neck and bottom of the bottle illustrate portions of the beverage bottle and form no part of the claimed design.
